[57] CLAIM

The ornamental design for a can compactor, as shown and described.

DESCRIPTION

FIG. 1 is a front view of a can compactor showing my new design; the handle being shown in broken lines for illustrative purposes only;

FIG. 2 is a top view thereof;

FIG. 3 is a side view taken from the left of FIG. 1, the side opposite being a mirror image thereof;

FIG. 4 is a bottom view thereof.

FIG. 5 is a perspective view thereof.

FIG. 1

FIG. 2

FIG. 3
